PAUL P. HEIN, OF NEW YORK, N. Y.

SAFETY GAS-TIP.

1,295,495.

Specification of Letters Patent. Patented Feb. 25, 1919.

Application filed May 16, 1918. Serial No. 234,969.

To all whom it may concern:

Be it known that I, PAUL P. HEIN, a citizen of the United States, and a resident of the city of New York, borough of Manhattan, in the county and State of New York, have invented a new and Improved Safety Gas-Tip, of which the following is a full, clear, and exact description.

This invention relates to gas tips, and has particular reference to a gas fitting or appliance that will close automatically and so stop the flow of gas in the event that the flame is extinguished by any means.

It is a well known fact that the flame of an ignited gas tip is liable to be extinguished by wind or a draft blowing against it, by the dropping of the pressure of gas at the source, especially when the gas flame is turned low, and by other causes, and it is also a well known fact that the valve of a gas tip as ordinarily constructed is apt to be struck or otherwise turned inadvertently when there is no intention to ignite the gas, thereby leaving the valve open and permitting the gas to escape. It follows, therefore, that there is not only a waste of gas but the more important fact of the danger of asphyxiation that is likely to result.

Among the objects of the invention therefore is to provide a simple and certain expedient whereby the valve will be automatically closed almost instantly after the flame is extinguished or will be returned immediately to its closed position in the event of inadvertent or accidental opening of the valve.

I am aware that numerous devices have been proposed heretofore for this same general purpose, but so far as I have been advised the prior devices are of an expensive and complicated nature and so subject to criticism on two main grounds: First, they are too expensive to be installed by the ordinary common users of gas tips for their protection, and secondly being of a delicate and complicated nature are apt to fail when they should be relied upon. It follows, therefore, that another object aimed at in this construction is to provide an attachment for a gas tip that is so simple and cheap in its make-up that the cost for installation is practically negligible; also from the nature of the attachment set forth herein it cannot fail to operate at the desired time to close the valve.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical sectional view showing my improved gas tip complete, the valve and the parts coöperating therewith being shown in normal closed position, while dotted lines indicate the approximate position of the locking lever when the valve is held open thereby.

Fig. 2 is a side elevation of the same as seen from the left side of Fig. 1; and

Fig. 3 is a horizontal section on the line 3—3 of Fig. 1.

Referring now more particularly to the drawings, I show a gas attachment comprising a burner body 10 having an internally threaded flange 11. This burner is designed with reference to the threaded flange 11 to be substituted for the usual burner tube which carries the tip 12 or to be added if desired as an extension to the usual valve body in present installations. In other words where a building is equipped with gas appliances all that is necessary to install this improvement is to unscrew each standard burner tube from the fixture having the valve and apply this improvement to the same fixture leaving the original valve. In new installations, however, this improvement will be applied directly to the fixtures so that only one valve will be employed at each fixture.

The valve proper shown at 13, having a transverse hole 13' registering with the bore 14 of the burner, is or may be of any approved construction so far as the control of the flow of gas through the bore 14 is concerned. As usual it is provided with a finger piece 15 at one end for the usual manipulation by hand either to turn the valve to ignite the gas or to extinguish the gas in the usual way. The stop lug 16 coöperates with a shoulder 17 in any well known manner to limit the rotary movement of the valve in the closing direction.

At any convenient place, preferably at

the end thereof opposite the finger piece 15, the valve 13 is provided with a friction member indicated in the form of a disk 18 having an outwardly directed flange 19.

5 This disk or friction member 18 is shown fixed with its center in the axis of rotation of the valve 13, it being held in fixed position on the valve by means of a screw 20, or its equivalent. This friction member may 10 be stamped conveniently out of relatively thin cheap sheet metal. The flange 19 may be relatively shallow but provides a guard or keeper for a resilient shoe 21 which is adapted to bear against the outer face of the disk 18. The shoe 21 is indicated in elevation in Fig. 2 and comprises preferably a plurality of independent fingers the ends of which are adapted to bear against either the outer face of the disk 18 or inner surface 15 of the flange 19, or both of these surfaces, while the gas flame is burning. When, however, the device is in normal cold condition and the valve is closed the shoe may bear very lightly against the outer face of 20 the disk or even be spaced slightly therefrom so that the flange 19 serves to prevent any possible lateral movement of the shoe with respect to the axis of the valve and friction member.

25 30 As a preferred means for actuating the shoe I provide an expansion member 22 in the nature of a simple straight bar of metal such as steel or common iron. One end 22' of this expansion bar has threaded engagement in the upper end of a standard 23 while the other end of the bar abuts squarely against the upper shorter arm 24^a of a lever 24 of the first class. This lever is pivoted at 25 in the fork 26 of a standard 27 formed 35 on the side of the burner diametrically opposite the standard 23. The aforesaid resilient shoe 21 is fixed upon or carried by the extreme lower end of the arm 24^b of the lever, or at least the shoe is held in the friction member in some convenient manner so as to be actuated by the inward movement of the lower end of said longer arm.

40 The parts thus far described are designed with respect to one another so as to occasion 45 little or no frictional contact between the shoe 21 and disk 18 when the bar 22 is cold, but when the bar is hot the increment added to its length by its expansion will cause the bar to bear against the shorter arm of the lever causing the longer arm thereof to approach the dotted line position on Fig. 1, and thus cause the shoe to bear upon the disk 18 with sufficient friction to hold the valve open. Almost instantly, however, 50 upon the cooling of the bar 24 the contraction thereof will relieve the pressure of the shoe on the disk. The threading of the bar into the upper end of the standard 23, however, provides for longitudinal adjustment 55 of the bar 22 so as to delicately determine the coöperation of the parts as intended, either at the time of assemblage or at any subsequent time.

60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

With the foregoing detail description of the mechanism a brief statement of the operation should suffice. If the valve 13 is the only valve employed the operator to light the gas will apply the match or taper with one hand while he opens the valve slowly so as to turn the gas on moderately with his other hand. It is well understood that when the gas pressure is high the gas should be turned on moderately to prevent the flow of gas blowing out the taper or match. Therefore with the valve opened slowly and the gas lighted while the pressure is low, the heat developed by this time and with the turning on of the gas to full flow and adjusting the valve to the desired volume of flame, the expansion member 22 will have been sufficiently heated to cause the friction shoe to grip the disk and hold the valve in the position to which it is turned by the operator, hence the operator gives no attention whatever to the automatic friction or holding devices. If the gas is to be turned out by hand in the usual way the operator turns the valve accordingly bringing the stop 16 against the shoulder 17. The design of the friction disk and shoe is such that the frictional grip incident to the heated bar 22 is not sufficient to prevent this closing of the valve by hand. When, however, the flame is extinguished unintentionally by any means the bar 22 contracts sufficiently within two or two and one half seconds to release the frictional grip between the shoe and the disk, so setting the spring 28 free to close the valve. If my improvement has been applied as an auxiliary to an existing gas valve the standard valve may be left open all the time, or if it is desired to manipulate it the operation will be as follows: The standard valve is first opened and then the operator manipulates the safety valve as above described in lighting the gas. To turn off the gas the operator may close the standard valve whereupon the automatic valve will immediately thereafter close automatically.

I claim:

1. The combination of a gas burner, a

- 5 rotary valve fitted therein to control the flow of gas, a friction member fixed to the valve and rotatable therewith around the axis of the valve, a shoe coöperating with said friction member, an expansion member heated by the gas flame, means actuated by the expansion of the expansion member and acting upon said shoe to cause it to grip the friction member with sufficient friction 10 to hold the valve open, and means acting upon the valve to close the same automatically when the grip aforesaid upon the friction member is relieved incident to the cooling of the expansion member.
- 15 2. The combination of a gas burner, a rotary valve fitted therein, means connected to the valve to automatically close the same, a friction disk concentric with the valve and

lying in a plane perpendicular to the axis thereof, a resilient shoe coöperating with 20 the side of the disk remote from the burner, a lever of the first class having longer and shorter arms, a pair of standards carried on diametrically opposite sides of the burner, said lever being pivoted upon one of said 25 standards, and an expansion member carried by the other standard and having its free end abutting against the shorter arm of the lever across the plane of the gas flame whereby the expansion member when heated 30 will cause through said longer arm the gripping engagement between the shoe and the disk to resist the action of the automatic closing means.

PAUL P. HEIN.
